UNITED STATES PATENT OFFICE.

ANTON WEDL, OF NEW YORK, N. Y.

DESIGN FOR A TABLE NAPKIN OR ARTICLE OF SIMILAR NATURE.

Application filed November 19, 1925. Serial No. 15,469. Term of patent 3½ years.

To all whom it may concern:

Be it known that I, ANTON WEDL, a citizen of the United States, residing at New York city, county and State of New York, have invented a new, original, and ornamental Design for a Table Napkin or Article of Similar Nature, of which the following is a specification, reference being had to the accompanying drawing, forming part thereof.

The figure is a plan view of a napkin showing my new design. The detailed fragmentary showing of the design is continued around the entire article as indicated by the dotted lines. The design is applicable to similar articles of table linen, and the mode and effect of such application will be obvious from the example given.

I claim:

The ornamental design for a table napkin or article of similar nature, substantially as shown and described.

ANTON WEDL.
